[57] CLAIM

The ornamental design for an adjustable needlework support, as shown and described.

DESCRIPTION

FIG. 1 is a perspective view of an adjustable needlework support showing my new design;

FIG. 2 is a front elevation thereof with the support frame in a partially elevated position;

FIG. 3 is a rear elevation thereof in the same position as in FIG. 2;

FIG. 4 is a side elevation thereof in the same position as in FIGS. 2 and 3;

FIG. 5 is a top plan view thereof in the same position as in FIGS. 2-4;

FIG. 6 is a bottom plan view thereof;

FIG. 7 is a top plan view thereof with the support frame collapsed against the base; and

FIG. 8 is a side elevation thereof in the same position as in FIG. 7.

FIG. 1

FIG. 2

*FIG. 3**FIG. 4**FIG. 5***FIG. 6****FIG. 7****FIG. 8**
